UNITED STATES PATENT OFFICE.

WILLIE H. DAVIS, OF ACCOVILLE, WEST VIRGINIA.

MINER'S BREASTPLATE.

1,383,909.

Specification of Letters Patent. Patented July 5, 1921.

Application filed May 21, 1920. Serial No. 383,197.

To all whom it may concern:

Be it known that I, WILLIE H. DAVIS, a citizen of the United States, residing at Accoville, in the county of Logan and State 5 of West Virginia, have invented certain new and useful Improvements in Miners' Breast-plates, of which the following is a specification.

This invention relates to improvements in 10 drilling apparatus of the mining type and has for its object to provide an improved breast plate for miners' use by which the necessary pressure may be exerted upon the drill bit to expedite drilling of rock or other 15 material.

A further object of the invention is the provision of a breast plate wherein the drill supporting element is afforded a wide 20 range of movement with relation to the breast plate due to the utilization of an improved type of universal joint whereby convenience and comfort are afforded the miner 25 in drilling in locations which are difficult of access.

With these and other objects in view, the 30 invention consists in certain novel features of construction as hereinafter shown and described and then specifically pointed out in the claims, and in the drawings illustrative of the preferred embodiment of the invention,

Figure 1 represents a perspective view of the improved breast plate, and

Fig. 2 represents a longitudinal sectional 35 view therethrough.

Referring to the drawing in detail, where in similar reference numerals designate corresponding parts throughout the several views, the numeral 5 indicates the breast 40 plate which consists of the slightly curved medial portion and the turned ends 6 the shape of the entire plate being such as to conform to the general shape of the breast of the miner. The plate is provided with 45 longitudinal reinforcing ribs 7 extending from a point adjacent the center to the ends thereof which are designed to increase the strength and rigidity of the plate without unduly increasing the weight thereof.

50 A socket designated generally by the numeral 8 is located centrally of the convex face of the plate 5 between the terminals of the ribs 7 and consists of base and cap plates 9 and 10, respectively, which are rigidly

and detachably connected with the breast 55 plate by bolts or equivalent fastening devices 11.

The base plate 9 is provided with a central transverse aperture 12 which is tapered and decreases in diameter toward the breast 60 plate 5.

The portion of the cap plate contiguous to the aperture in the base plate is bulged outwardly and apertured providing a substantially semi-spherical cup 13. 65

The drill supporting element 14 is provided at one terminal with adequate means to support the drill in connection with which the breast plate is to be used, according to the type of drill in use. In the present embodiment of the invention the drill support is illustrated as being provided terminally with a socket although this feature of the invention is capable of such modification as will adapt the device for use in connection with various types of drills. 70

The opposite terminal of the drill support is provided with a substantially spherical head 15 which is partially accommodated within the aperture 12 of the base plate and 80 in the cupped portion 13 of the cap plate, being afforded relatively wide range of movement with relation to the breast plate and having its end thrust limited in one direction by the walls of the aperture in the 85 base plate and in the other direction by the walls of the cupped portion of the cap plate. The base plate 9 is arranged to receive the end thrust of the drill support 14 and thus reinforces the breast plate at the point of 90 stress.

The principal advantage in the use of the improved breast plate resides in the comfort afforded the miner in drilling operations due to the possibility of utilization of the 95 chest in exerting the proper pressure upon the drill bit. Furthermore, due to the utilization of the universal joint connecting the drill supporting element with the breast plate, the latter is afforded a wide range of movement with relation to the drill bit permitting drilling operations to be carried on in such locations as are otherwise difficult of access. For instance, when the miner is compelled to drill when in a stooping position and the chest is consequently inclined forwardly, the breast plate may be adjusted 100 so as to lie flat against the chest and the 105

drill bit is moved angularly relative to the breast plate until it is in a horizontal position.

What I claim is:

1. In combination, a breast plate, a tool supporting element, and means connecting the breast plate with the supporting element and permitting universal movement of the latter whereby the tool supporting element 10 and tool mounted therein may be moved to various angular positions while the breast plate is maintained flat against the chest.

2. In combination, a breast plate having turned ends to partially embrace the chest, 15 a tool supporting element, and means detachably connecting the breast plate with the supporting element and permitting universal movement of the latter whereby the tool supporting element and tool mounted

therein may be moved to various angular 20 positions while the breast plate is maintained flat against the chest.

3. In combination, a breast plate, a base plate secured thereto having a tapered aperture, a cap plate secured to the base plate 25 having the portion adjacent the aperture in the base plate cupped, a tool supporting element, and a head at the extremity of the tool supporting element partially received within the aperture of the base plate and within the cupped portion of the cap plate, 30 said base plate constituting a reinforcement for the breast plate and arranged to receive the thrust of the supporting element.

In testimony whereof, I affix my signature 35 hereto.

WILLIE H. DAVIS.
